UNITED STATES PATENT OFFICE.

EDWIN C. BISHOP, OF HARTFORD, CONNECTICUT.

EXTENSIBLE TRESTLE.

SPECIFICATION forming part of Letters Patent No. 637,847, dated November 28, 1899.

Application filed March 28, 1899. Serial No. 710,777. (No model.)

To all whom it may concern:

Be it known that I, EDWIN C. BISHOP, a citizen of the United States, residing at Hartford, in the county of Hartford and State of Connecticut, have invented certain new and useful Improvements in Extension-Trestles, of which the following is a specification.

This invention relates to those trestles provided for the use of masons, carpenters, decorators, and the like artisans and which are extensible, so that staging may be built upon them at many different levels.

The object of this invention is to construct a very simple and convenient trestle of this nature that will be exceedingly strong, reliable, and durable.

This invention resides in a trestle that has sections with the usual steps or rounds so hinged together that they may be closed parallel with each other or opened at an angle with each other, with a sliding section having ordinary steps or rounds located between the hinged sections, the hinged sections being provided with lugs and the sliding section having shoulders adapted to be engaged by the lugs when the trestle is in use in such manner that the greater the weight upon the trestle the firmer will the sliding section be supported.

Figure 1 of the accompanying drawings shows a side elevation of a trestle that embodies the invention with the sliding section extended for use. Fig. 2 shows a front elevation of the extended trestle. Fig. 3 shows a side elevation of the same trestle closed, and Fig. 4 is a detail view showing on larger scale a hinged plate and the lugs secured to the hinged sections and the shoulders of the sliding section.

The hinged sections are each built of a pair of side rails 1, made of wood or any other desired material, with common rounds 2 extending between these rails. These sections are connected near their upper ends by hinge-plates 3, so that they may be spread outward and stand at an angle when in use, as shown in Fig. 1, or fold parallel for storage, as illustrated in Fig. 3. Spreading-toggles 4 are attached to the side rails for holding these sections open.

The sliding section, that is movable between

the hinged sections, is built of a pair of side rails 5, with rounds 6 extending between them. Each of the side rails of the sliding section is in the plane of the side rails of the hinged sections, and in the outside edge of the rails of the sliding section is a longitudinal groove 7. On the back of the hinge-plates are tongues 8, that project into these grooves. This arrangement holds the hinged plates so that the hinged sections will open and close easily and uniformly and so that the extensible section will slide smoothly and be held securely.

Secured to the beveled upper ends of the side rails of the hinged sections are lug-plates 9, that have supporting-lugs 10, and formed in the edges of the side rails of the sliding section are notches with supporting-shoulders 11, of which there may be any desired number.

When the hinged sections are closed together, the sliding section may be freely moved between them; but when the hinged sections are opened the lugs secured to their upper ends will pass into notches below supporting-shoulders on the edges of the side rails of the sliding section.

When used, the sliding section is lifted to the desired height and then the hinged sections are spread apart, so as to brace each other. In this relation they are held spread by the spreading-toggles. As the hinged sections are spread the supporting-lugs attached to their upper ends project into notches beneath the proper supporting-shoulders on the sliding section. The supporting-lugs on the hinged sections cannot work out from beneath the supporting-shoulders on the sliding section until the hinged sections are closed, and the hinged sections cannot again be closed until the spreading-toggles are unlocked.

The parts of this trestle are very simple, strong, and durable. There are no springs or working parts that will wear, break, or become loose. The sliding section may be locked at any desired height, and staging may be built upon any of the rounds of the hinged sections or of the sliding section. The weight upon the sliding section, tending to cause it to drop, is sustained by the engagement of the solid shoulders of the sliding section with the strong lugs attached to the ends of the hinged

sections, and these parts cannot accidentally become disengaged, for the weight upon the sliding section will tend to cause the hinged sections to spread at the bottom and close at 5 the top, and this causes a closer engagement of the lugs and shoulders. By this means the greater the weight upon the extending part of the trestle the firmer will the sliding section be supported. Thus all liability of col- 10 lapse is averted.

I claim as my invention--

1. An extensible trestle having three sections, each consisting of a pair of side rails joined by rounds, with shoulders formed on 15 the edges of the side rails of the middle section and lugs projecting from near the upper ends of the side rails of the two outer sections in position to engage with the shoulders on the adjacent side rails of the middle section, 20 plates outside of the side rails of all three sections, and bolts passing through the plates and pivotally connecting the side rails of the

two outer sections with the plates, substantially as specified.

2. An extensible trestle having three sec- 25 tions, each consisting of a pair of side rails joined by rounds, with shoulders formed on the edges of the side rails of the middle section and lugs projecting from near the upper ends of the side rails of the two outer sections 30 in position to engage with the shoulders on the adjacent side rails of the middle section, plates outside of the side rails of all three sections, bolts passing through the plates and pivotally connecting the side rails of the two 35 outer sections with the plates, and tongues extending from the plates into grooves in the outside of the side rails of the middle section, substantially as specified.

EDWIN C. BISHOP.
